UNITED STATES PATENT OFFICE.

JOHN M. SCHILLING, OF CHICAGO, ILLINOIS.

INTERCHANGEABLE-LETTER BULLETIN-BOARD.

1,146,528.

Specification of Letters Patent. Patented July 13, 1915.

Application filed May 7, 1913. Serial No. 766,090.

To all whom it may concern:

Be it known that I, JOHN M. SCHILLING, a citizen of the United States, residing at Chicago, in the county of Cook and State 5 of Illinois, have invented certain new and useful Improvements in Interchangeable-Letter Bulletin-Boards, of which the following is a specification.

This invention relates to improvements in 10 interchangeable letter bulletin boards and its object is to produce a device of this class comprising a frame or support to which a plurality of transverse bars, spaced apart, are secured; said bars being adapted to re- 15 movably retain in set position a plurality of letter plates which may be so positioned as to form a word or words, signs or symbols. Means are provided for keeping the said letters plates, which are preferably sus- 20 pended from the said bars, in alinement with each other and for retaining them in operative position during and after alterations in the positions of the supporting means for said letter plates.

25 With the foregoing and other objects in view the invention consists in the combination and arrangement of parts to be herein-after fully described in the following specification, pointed out in the claim and illus- 30 trated in the accompanying drawing which forms a part of said specification and in which—

Figure 1 is a front elevation of a portion of the frame or supporting means by 35 which the letter plates are carried. Fig. 2 is a rear elevation of the same. Fig. 3 is a detail of a portion of one of the supporting bars, enlarged. Fig. 4 is an end elevation of Fig. 3. Fig. 5 is a section taken 40 on line 5—5 of Fig. 3. Fig. 6 is a rear view of Fig. 3. Fig. 7 is an enlarged detail of the strip and bar just before they are clamped together. Fig. 8 is a front elevation of a portion of one of the strips 45 employed. Fig. 9 is an end view of Fig. 7 showing the parts fastened together. Fig. 10 is a view of Fig. 9 secured to the frame or support employed. Fig. 11 is a rear view of Fig. 10. Fig. 12 is a front elevation 50 of one of the letter plates. Fig. 13 is an edge view of Fig. 8. Fig. 14 is an edge view of Fig. 12. Fig. 15 is an end elevation of the device with the supports removed showing that the letter plates will hang ver- 55 tically regardless of the angle of their supports.

Like reference characters indicate corresponding parts throughout the several views.

In one embodiment of my invention I provide a frame or support composed of a pair 60 of uprights 1, 1 to which a plurality of bars 2, preferably spaced apart, are secured by screws or other suitable fastening means 3. A pair of strips 4, 4 secured to the uprights 1, 1 are disposed between the same and the bars 2 are apertured as at 5 to permit passage therethrough of the screws 3. Each bar 2 is preferably formed of a single strip of material, metal or fiber, which along one longitudinal edge is bent back almost upon 70 itself as at 6 forming a rearwardly extending flange whose base 7 forms the upper edge of bar 2 and which is bent forwardly out of the plane of the body of the bar 2; the opposite longitudinal edge of the bar 2 is 75 bent back in the direction of the portion 6 approximately at an angle of 45 degrees with said bar as at 7^a forming an angular flange. The foregoing is the preferred formation of each of the bars employed and 80 they are arranged one above the other and spaced a very slight distance apart. Each end of each bar 2 is formed with a pair of elongated slots 8, 8 preferably disposed above and below the aperture 5 in that bar. 85 Each strip 4, to which the several bars are directly fastened, is formed with a plurality of integral lugs 9 which are punched out therefrom leaving apertures 10 in said strips and said lugs 9 are adapted to be inserted in the apertured portions 8 of the bars 2 whereby the said bars and strips are 90 secured together.

11 is the letter plate, one edge 12 of which is bent back to form a flange by which 95 said plate is removably secured to the bar 2. The flange 12 is inserted over the forwardly bent portion 7 of the bar 2 and should the uprights 1, 1 with bars 2 be tilted or inclined forward the flange 12 of plate 11 100 will swing toward the flange 6 of bar 2 while the several letter plates remain in alinement with each other and in operative position.

While the foregoing is the preferred embodiment of my invention I, nevertheless, reserve the right to make such alterations as may be found expedient in the commercial use of my invention within the scope of the claim.

105 What is claimed is:—

110 In an interchangeable letter bulletin board

the combination with vertical supports, of bars arranged one above the other on the supports and spaced apart, each bar having its upper edge portion inclined forwardly and upwardly and then turned back upon itself and a plurality of letter plates having rearwardly and downwardly extending flanges on their upper edges whereby they may be movably supported upon the upper edge portions of said bars, the angles between each letter plate and its flange being large enough to allow the letter plate

to swing forwardly when the bulletin board is tilted forwardly and thereby maintain a vertical position.

15

In testimony that I claim the foregoing as my own I have hereto affixed my signature in the presence of two subscribing witnesses.

JOHN M. SCHILLING.
